FRAME FOR SWINGS

David Saint, Elverson, Pa., assignor to Graco Metal Products, Inc., Elverson, Pa.

Filed Oct. 13, 1971, Ser. No. 189,066

Term of patent 14 years

Int. Cl. D6—06

U.S. Cl. D6—191

FIG. 1 is a perspective view of a frame for swings showing my new design;

FIG. 2 is a rear elevational view of the frame;

FIG. 3 is a side elevation view of the frame; and

FIG. 4 is a top plan view of the frame.

I claim:

The ornamental design for a frame for swings, as shown.
